UNITED STATES PATENT OFFICE

144,590

DESIGN FOR A COMBINATION TABLE AND CABINET

Gerhard R. Schutes, Saginaw, Mich., assignor to Spartan Aircraft Company, Tulsa, Okla.

Application November 19, 1945, Serial No. 123,859

Term of patent 3½ years

(Cl. D33—14)

To all whom it may concern:

Be it known that I, Gerhard R. Schutes, a citizen of the United States, residing at Saginaw, in the county of Saginaw and State of Michigan, have invented a new, original, and ornamental Design for Combination Table and Cabinet, of which the following is a specification, reference being had to the accompanying drawing, forming part thereof.

In the drawing:

Fig. 1 is a perspective view of a combined table and cabinet looking downwardly toward one corner thereof and with the drop leaves in raised position and showing my new design.

Fig. 2 is a similar view on a smaller scale looking downwardly from the diagonally opposite corner thereof and with the leaves in folded position.

I claim:

The ornamental design for a combination table and cabinet, as shown.

GERHARD R. SCHUTES.
